POST HOLE DIGGING MACHINE

Filed April 12, 1930

UNITED STATES PATENT OFFICE

NORMAN A. WRIGHT, OF PONTIAC, MICHIGAN, ASSIGNOR TO PONTIAC TRACTOR COMPANY, OF PONTIAC, MICHIGAN, A CORPORATION OF MICHIGAN

POST HOLE DIGGING MACHINE

Application filed April 12, 1930. Serial No. 443,885.

The present invention pertains to a novel post hole digging machine, and one of the principal objects is to provide a construction of this character wherein the digging mechanism may as a unit be adjusted with reference to the chassis in order to dig a plumb hole regardless of the fact that the chassis may be standing on unlevel ground.

It is a further object of the invention to drive the digger mechanism from a propelling motor fixedly mounted on the chassis, and this mode of operation is in effect at all times notwithstanding the adjustability of the digger mechanism. Still another object of the invention is to provide a mechanism for driving the cable drum positively in either direction, as required by law in many localities.

The invention is fully disclosed by way of example in the following description and in the accompanying drawings, in which—

Figure 1 is a side elevation of the machine;

Fig. 2 is a detail plan view, partly in section;

Fig. 3 is a detail transverse vertical section, partly in elevation, and

Fig. 4 is an enlarged detail of Figure 1.

Reference to these views will now be made by use of like characters which are employed to designate corresponding parts throughout.

The machine embodies a chassis 1 mounted on wheels 2 and supporting a motor 3 fixedly thereon. At one end of the chassis 3 is provided a boom 4 equipped in the usual manner with a cable 5. This cable winds on a drum 6 suitably supported by the chassis.

A set of four bearings 7 stand on the chassis and support a pair of aligned shafts 8 and 9 which are spaced at their confronting ends as clearly shown in Figures 2 and 3. The inner ends of the shaft support a gear box 10 and further carry a pair of bevel gears 11 and 12 disposed within the box. To one of the intermediate sides of the box is secured a sleeve member 13. A shaft 14 for operating digger mechanism presently to be described passes through the sleeve and box 10 and has its free end journaled in the opposite wall of the box. This shaft also

carries an intermediate gear 16 meshing with the gears 11 and 12 as also shown in Figure 2.

The digger mechanism is of known construction and is contained within a casing 17 resting in a cradle 18. A pair of brackets 19 are supported by the chassis for maintaining one of the ends of the cradle which has depending screws 20 passing through the brackets, each screw being equipped with a pair of adjusting nuts 21 at opposite sides of the bracket, whereby the elevation of the rear end of the cradle may be adjusted. The forward end of the casing 17 is supported by a frame structure including a pair of right angular end members 22 joined by an intermediate bar 23. One face of the bar 23 is attached to the casing 17, while the other face carries a ring 24 of angular cross section rotatable on a collar 25 on the forward end of the sleeve 13. The end arms 26 of the members 22 are slotted at 27 to receive square blocks 28 mounted on the outer ends of the shafts 8 and 9 and adapted to turn thereon. In this position the frame serves as a brace to prevent the shaft 14 from bending laterally and because of the slots 27 is permitted to turn with the casing 17 around the shaft 14 in axial adjustments of the casing.

The digger mechanism further includes a vertical shaft 29 carrying a suitable tool 30 at its lower end and adapted to be driven by the mechanism within the casing 17. It will now be apparent that the shaft 29 may be adjusted in one plane by the swinging of the frame 22—26 on the shafts 8 and 9 and in the other plane by the swivel motion of the casing 17 about the shaft 14, the adjustment in either or both planes being made by means of the pairs of nuts 21.

The shaft 8 carries a pulley 31 connected by means of a belt 32 to the motor 3. The shaft 33 of the drum 6 is equipped at one end with a gear 34 housed in a casing 35. In this casing is journaled a shaft 36 carrying a worm 37 meshing with the gear 34 and of such pitch that it cannot be driven by the gear in response to a tendency to turn reversely.

through a weight on the boom end of the cable 5.

The shafts 8 and 9 further carry loose clutch members 38 and 39 respectively which are connected by gear and sprocket devices 40 to the ends of the shaft 36. On the shafts are splined driving clutch members 41 and 42 respectively held by means of arms 43 and a shifter rod 44 at a greater distance apart than the distance between the members 38 and 39. Thus, it is possible to release both driving members simultaneously from the loose members and engage only one driving member with its cooperating loose member at a time.

It will be evident that the shafts 8 and 9 turn in opposite directions by reason of the intermediate gear 16 and that the worm 37 and hence the drum 6 may be turned positively in opposite directions by selection of the clutches.

Although a specific embodiment of the invention has been illustrated and described, it will be understood that various alterations in the details of construction may be made without departing from the scope of the invention, as indicated by the appended claims.

What I claim is:—

- 30 1. In a post hole digging machine, a chassis, a shaft mounted thereon, a frame having arms slideable on the ends of said shafts, a digger mechanism casing having one end journaled in said frame, means for vertically adjusting the other end of said casing, and a shaft in said casing geared to the first named shafts.
- 35 2. In a post hole digging machine, a boom, a cable on said boom, a drum on which said cable is wound, a motor, means for positively turning said drum in opposite directions comprising a pair of aligned shafts, one of which is geared to said motor, beveled pinions on the confronting ends of said shafts, an intermediate pinion meshing with the first named pinions whereby said shafts are caused to turn in opposite directions, clutch members loose on said shafts and geared to said drum, cooperating driving clutch members keyed on said shafts and adapted to selectively engage said loose members, a frame having arms slideable on the ends of said shafts, a digger mechanism casing having one end journaled in said frame, means for vertically adjusting the other end of said casing, and a shaft in said casing and carrying said intermediate pinion.

In testimony whereof I affix my signature.
NORMAN A. WRIGHT.
